UNITED STATES PATENT OFFICE.

MYRON J. FERREN, OF WASHINGTON, DISTRICT OF COLUMBIA.

CAN-HEAD-CUTTING MACHINE.

No. 869,075.

Specification of Letters Patent.

Patented Oct. 22, 1907.

Application filed April 18, 1907. Serial No. 368,828.

To all whom it may concern:

Be it known that I, MYRON J. FERREN, a citizen of the United States, residing at Washington, District of Columbia, have invented certain new and useful Improvements in Can-Head-Cutting Machines, of which the following is a specification, reference being had therein to the accompanying drawing.

My invention relates to machines for cutting the heads of cans of the type disclosed in United States Letters Patent No. 836,744, granted to me November 27, 1906.

One of the primary objects of my present invention is to provide a mechanism in which the movement of the can will not interfere to any extent with the movement of the cutter and vice versa.

Other objects of the invention will become apparent as the preferred embodiment, illustrated in the accompanying drawings, is described in detail hereinafter.

The invention includes the combination and arrangement of component parts to be hereinafter described and particularly pointed out in the claims.

In the accompanying drawings which illustrate one embodiment of my invention Figure 1 is a perspective view of the device. Fig. 2 is a side elevation thereof. Fig. 3 is a rear elevation. Fig. 4 is a detail sectional view. Fig. 5 is a detail view of a modification. Fig. 6 is a detail view of a modification and Fig. 7 is a detail view of the indicator plate.

The frame of the device may be of any suitable form, 30 that illustrated including a base *a* supported by suitable legs and two standards *b c* rising from the base.

The can to be operated upon is directly shifted by two knurled disks *d e* which engage the peripheral beads at its opposite ends. As herein illustrated, the upper 35 disk is fixed to one end of a shaft *f*, suitably journaled in the standards *b c*, carrying a bevel pinion *g* which intermeshes with a companion pinion on the upper end of a counter-shaft *h* which is stepped at its lower end in a suitable socket in the base *a* and is journaled at 40 its upper end in a horizontal web extending between the standards *b c* and preferably cast integral therewith. The lower disk *e* is arranged in vertical alignment with the disk *d* and is fixed to the outer end of a shaft journaled intermediate of its ends in a bracket 45 *i*, this shaft carrying at its inner end a bevel gear *m* permanently held in mesh with a companion bevel-gear splined to the counter-shaft *h*. The bracket *i* and associated parts are vertically adjustable for the purpose of moving the disk *e* toward and from the 50 disk *d* in order to accommodate cans of varying heights and this adjustment is effected in the illustrated form of the invention by means of a rack bar *n* depending from the bracket *i* which is engaged by a pinion *o* carried by a hand operated shaft *p*. This shaft is suitably 55 journaled in the base and carries a hand crank *q*. For

holding the parts in adjusted position a pawl and ratchet are employed.

As illustrated in Figs. 1, 2 and 3 the ratchet, designated *r*, is fixed to the shaft *p* and is engaged by a pawl *s* pivoted to the base *a*. The front portion of the 60 pawl is pressed in engagement with the ratchet by a suitable spring and the pawl is disengaged from the ratchet by pressing upon an extension or tail piece projecting beyond its pivot.

In the construction illustrated, in Fig. 5, the ratchet *r'* is fixed to the base and the pawl or detent *s'* is carried by the hand crank and is shifted out of engagement with the ratchet by a finger piece *s''* operated by the action used in grasping the handle of the crank *t'*.

A platform *t* is carried by the bracket *i*, is preferably 70 cast integral therewith and serves to assist in supporting the can under operation.

To further assist in retaining the can in place during the cutting action, a rest is provided at the rear of the disks *d e* and closely adjacent thereto. As illustrated 75 in Figs. 1, 2 and 3, this rest is provided by circular flanges *d' e'* on the disks *d e* respectively and as illustrated in Fig. 6 the rest is provided by a plate *g'* secured to the standard *b* and having a slot *g''* to permit of the movement of the shaft *f* in the adjustment of the disk *e*. 80 The rest thus provided serves to prevent the can turning about an axis through the points of engagement of the disks *d e* therewith, and thereby acts to prevent the can from twisting or turning out of engagement with these disks.

The upper disk *d* is preferably yieldingly pressed toward the lower disk by suitable means, that herein illustrated, in Fig. 4, comprising a spring *d''* held in a pocket in the standard *b* bearing at one end upon one end of the shaft and having a bearing at its opposite end 90 against a plug *d''* threaded in the mouth of the pocket. This construction admits of the can rotating means accommodating irregularities in the beads at the ends of the cans. The range of movement of the disk *d* is preferably in excess of the maximum required to accommodate such irregularities and it is desired that this disk occupy, when in engagement with the can, a position substantially centrally between the limits of its movement. To readily attain this object a suitable indicator is associated with the shaft *f* which coacts 95 with a suitable graduation on the standard *b* to indicate the position of the shaft. This indicator is illustrated herein as a plate *a'*, is movably mounted on the standard *b*, is provided with a yoke *a''* engaging a hub on pinion *g*, and is provided with a finger *a'''* co-acting with a 100 mark *b x* on the standard *b*.

A cutter having a reciprocatory movement is employed in the illustrated embodiment of the invention, that shown, comprising a bar *u* guided on the front face of the standard *b* having its lower end provided with a 110

bevel knife edge working just in advance of the disk d and its upper end connected to a crank v carried by a shaft w journaled in the upper ends of standards b c .

As hereinbefore premised, my invention contemplates mechanism in which the movement of the can will not interfere with the movement of the knife and vice versa and in the illustrated embodiment of my invention this object is obtained by mechanism for converting a substantially constant movement of an actuating element into a step by step feed to the can feeding disk with intermediate intervals of rest, and into a reciprocatory movement of the knife timed to occur synchronously with said intervals of rest; periods of rest being provided between each reciprocation of the knife

10 actuating element into a step by step feed to the can feeding disk with intermediate intervals of rest, and into a reciprocatory movement of the knife timed to occur synchronously with said intervals of rest; periods of rest being provided between each reciprocation of the knife

15 timed to occur synchronously with the feed movements of the can. The mechanism shown in the illustrated embodiment of my invention for giving this movement comprises an element associated with shaft w for oscillating the same, an element associated with

20 shaft f for rotating it and an element designed to have a constant movement during the cutting of the can, common to both of the first named elements, and designed to successively co-act therewith and impart successive movements thereto. The element associated with the

25 shaft w is illustrated as a crank arm d^5 and the element associated with shaft k is illustrated as a star wheel k' . The element designed to have a continuous movement during the cutting operation is herein illustrated as a disk x provided with a series of radial strike arms x'

30 designed to successively co-act with the star wheel k' and crank d^5 to shift the same as the element x is rotated. In the illustrated embodiment of my invention a substantially continuous rotation is imparted to the element x during the cutting operation by means of a

35 suitable hand lever z . In the illustrated form of the invention the cutting movement of the knife occurs when the arm d^5 is shifted by direct engagement with one of the striker arms x' and the return of the knife to its initial position may be attained independently of

40 the striker arms or by mechanism positively operated by the striker arm. In the illustrated form of the invention mechanism is shown for utilizing both means. The return mechanism illustrated comprises an arm l pivoted to a bracket c' on the standard c , having a for-

45 ward end x designed to wipe along the edge of the crank arm d^5 and a tail piece x'' extending beyond its pivot and a helical spring y interposed between the forward end of the arm and the standard c which tends to draw the end of the arm l down and therethrough serves to

50 force the arm d^5 against a stop c' on the standard c . The tail piece of the arm is so positioned that immediately a striker arm passes out of engagement with the crank arm d^5 it will engage said tail piece and positively tilt the arm l to force the crank arm d^5 back against the stop

55 c' during which movement the cutter bar will be raised. As will be understood, the spring alone could be used and usually does operate, to return the crank arm d^5 to its initial position but this return is insured by the co-action of the striker arms with the tail of the wiper arm.

60 The spring employed is very light and is used primarily to hold the wiper arm in such position that the striker arms will co-act therewith.

As will be understood, all of the striker arms are entirely disengaged from the star wheel k' while one of the arms is in engagement with the crank-arm d^5 and vice

versa so that the during the movement of either the knife or can the other of the last named parts is at rest.

To reduce the wear on the contacting parts and to facilitate the operation of the machine, each of the striker arms x' is provided at its outer end with a laterally disposed roller x''' which directly engages the star wheel and crank arm b^5 .

70 To prevent the can from moving from between the disks d e , during the feeding action, a suitable stop, or rest, is adjustably secured to the standards which engages with the can in advance of the feeding disks. As illustrated in Figs. 1, 2 and 3, this rest, which is designated h' , engages the side of the can near the top of the same but the rest may be provided with a depending extension to co-operate with the can throughout the 80 entire length thereof, as illustrated in Fig. 6 in which view the extension is designated h^2 . The latter construction not only serves to resist any tendency of the can to tilt out of its proper perpendicular position but it also acts as a gage for the can in placing the same between the feeding disk so as to insure the can being placed in an exact upright position.

75 My improved device will be understood from the foregoing description and it will be appreciated that the particular parts and arrangement shown may be modified within a wide range without departing from the spirit and scope of the invention.

I claim:

1. In a can cutting machine a cutter, a driving element, means actuated by the driving element for intermittently feeding the can and means also actuated by the driving element for bringing the cutter into operative engagement with the can between the feeding movements.

2. In a can cutting machine, means for feeding the can step by step with intermediate periods of rest, and a cutter 100 movable into and out of engagement with the can during said periods of rest.

3. In a can cutting machine, means for feeding the can step by step with intermediate periods of rest, and a reciprocating cutter movable into and out of engagement 105 with the can during the periods of rest.

4. In a can cutting machine an operating element having a substantially continuous movement imparted thereto, means for supporting and rotating the can operated from said element to impart a step by step movement to the 110 can, a cutter, and means operated by said element to actuate the cutter at regular intervals.

5. In a can cutting machine, an operating element having a substantially continuous movement, means operated from the element for imparting successive feeding movements to the can with intermediate periods of rest, a cutter, and means operated from said element for actuating the cutter at intervals, said intervals occurring synchronously with the periods of rest of the can.

6. In a can cutting machine an operating element having a substantially continuous movement, means operated from the element for imparting successive feeding movements to the can with intermediate periods of rest, a cutter, means operated from the element for giving successive reciprocations to the cutter with intervals of rest, said intervals of rest being timed to occur synchronously with the feeding movements of the can, said reciprocations of the cutter being timed to occur synchronously with the periods of rest of the can.

7. In a can cutting machine, the combination with means for rotating the can comprising, disks engaging the can, a drive-shaft carrying one of the disks, and means for transmitting the movement of the shaft to the other of the disks, of a reciprocating cutter, a shaft, a crank carried by the shaft and connected to the cutter for reciprocating the cutter as the shaft is oscillated, an element having a substantially continuous movement, and means for alternately moving the can and knife during the movement of

- the element comprising a star wheel on the drive-shaft, a crank arm on the cutter shaft, and striker arms on said continuous moving element, relatively arranged that when one of the arms is in engagement with the star wheel or 5 crank arm the other arm will be out of engagement with the other of said parts.
8. In a can cutting machine a disk for moving the can, a drive-shaft for said disk, a reciprocatory cutter, a drive-shaft therefor, an operating handle having a substantially 10 continuous movement during the cutting operation, and means interposed between said element and said shaft for giving said shafts a series of alternating movements.
9. In a can cutting machine a disk for moving the can, a drive-shaft for said disk, a reciprocatory cutter, a drive-shaft therefor, an operating handle having a substantially 15 continuous movement during the cutting operation, and means for giving said shafts a series of alternating movements interposed between said element and said shafts, said interposed mechanism including a crank arm on the 20 cutter shaft, a star wheel on the disk driving shaft and a series of striker arms movable with the handle.
10. In a can cutting machine, means engaging the can to rotate the same, a drive shaft therefor, a star wheel carried by said drive shaft, a cutter, a cutter shaft, a crank 25 arm on the cutter shaft, a striker arm designed to shift said crank arm and star wheel, and a wiper arm co-acting with the crank arm for restoring the same to initial position, said wiper arm having a part projecting into the path 30 of movement of the striker arm and adapted to be actuated thereby following its disengagement from the crank arm.
11. In a can cutting machine means engaging the can for feeding it, a drive shaft for said means, an actuating element carried by the shaft, a cutter, a cutter shaft, a crank arm on said cutter-shaft, a stop therefor, a pivoted 35 wiper arm, a spring tending to hold the same against the crank arm and the latter against the stop, a striker arm designed to co-act with the crank arm to shift the same in one direction, and a tall piece on the wiper arm extending into the path of movement traversed by the striker arm
- immediately following the disengagement of the latter 40 from the crank arm.
12. In a can cutting machine a base, a standard rising therefrom having a guide slot therein, a bracket guided in said slot, an upper disk for engaging the can, a lower disk 45 for engaging the can, a shaft carrying the same journaled in said bracket, means for rotating the disk, and means for adjusting the bracket to move the lower disk toward and from the upper disk comprising a rack depending from the bracket, a pinion engaging the rack, a shaft carrying the pinion journaled in the base, and means for rotating the 50 shaft.
13. In a can cutting machine, the combination with a cutter, of upper and lower disks engaging the can for supporting and shifting the same, means for rotating the disks, and a rest engaging the side of the can near the top 55 of the same in advance of the disk, said rest having a vertical continuation co-acting with the side of the can throughout substantially the entire length thereof.
14. In a can cutting machine, the combination with a cutter and means for actuating the same, of a lower feeding disk, an upper feeding disk yieldingly pressed toward the lower disk, and an indicator associated with the upper disk.
15. In a can cutting machine, the combination with a cutter, and means for actuating the same, of a lower feeding disk, an upper feeding disk mounted to have movement 60 toward and from the lower feeding disk, a spring co-operating with the upper feeding disk for yieldingly pressing the same toward the lower feeding disk, and an indicator associated with the upper feeding disk for denoting the 65 position of the upper disk in its bearing, substantially as described.

In testimony whereof I affix my signature in presence
of two witnesses.

MYRON J. FERREN.
